SAFETY DEVICE FOR PUNCH-MACHINES.

1,095,497.

Specification of Letters Patent.

Patented May 5, 1914.

Application filed October 12, 1911. Serial No. 654,280.

To all whom it may concern:

Be it known that I, ERNEST L. GALE, Sr., a citizen of the United States, residing at Yonkers, in the county of Westchester and State of New York, have invented a new and useful Improvement in Safety Devices for Punch-Machines, of which the following is a specification.

My invention relates to safety devices for use in connection with punching machines.

An object of the invention is to provide means to prevent the operation of the machine except when the operator has both hands employed in a safe position, thereby preventing the danger of the punch being operated while the attendant's hand is beneath the die carrier.

A further object of the invention is to provide means to prevent the operation of the punch press while the pick-off device is beneath the die carrier.

Referring to the accompanying drawings, Figure 1 is an elevation view of a punching machine with the present invention applied thereto; Fig. 2 is a sectional view showing the die in plan; Fig. 3 is a diagrammatic view of the electrical devices and circuits employed.

The punch press is carried by a vertical standard or support S in the upper end of which is mounted a shaft 1 to which is secured a pulley P. The latter is connected, by means of a belt B, to any suitable source of power. A die carrier 4 is mounted on the bed plate 6 in position to coöperate with the punch carrier 3. The die D, as shown in Fig. 2, is provided with a central opening 5, so that the punching machine is adapted to produce laminations for an armature of a dynamo electric machine. In the process of making a punching, the pulley P is given one complete revolution, causing the punch carrier to be moved downward and coöperate with a die to form a punching and then lifted to its initial position.

The particular form of mechanism for reciprocating the punch carrier is not shown in detail as it does not, itself, form a part of the present invention, and varies widely in the different makes of machines to which my invention may be applied.

The pulley P is connected to operate the die carrier by means of a trip device comprising a pawl or cam lever 7 mounted on a pivot 8 and coöoperating with a cam 9 of the clutch, which connects the shaft 1 with the

mechanism for operating the die carrier. A spring 10 normally holds the lever 7 in its upward position in which the clutch is disconnected so that the pulley P runs free. 60 The trip device is operated by an electromagnet 11, connected through a lever 12 and a rod or link 13 to the lever 7. In circuit with the winding of the electromagnet 11 are two normally open push button switches 65 a and b. These switches are suitably located so that both hands of the attendant are required to close them and thereby effect the operation of the punch press. This forms a positive means for preventing the attendant 70 from accidentally placing either hand beneath the die carrier or any dangerous position while the press is operating. Push button switches a and b, as shown in Fig. 1, are located one above the other on the standard S, but they may be located in any other desired or convenient position, as, for example, at the edge of the bed plate, it being important, however, that they be placed far enough apart so that they cannot both be 80 operated at the same time with one hand.

The pick-off device for removing the punchings and scrap, is herein shown as comprising a lever 15 having a pivot 16 mounted on the bed plate 6. An electromagnet 17, 85 having extended pole pieces 18, is secured to the lever 15. A push button switch 19 is located in a handle 20 on the end of the lever 15. The switch 19 is in circuit with the winding of the electromagnet 17. A switch 90 21 in circuit with the electromagnet 11 comprises contacts carried by the lever 15 and the standard S, respectively. Electric current for operating the magnets 11 and 17 may be supplied from any convenient and 95 suitable source of electricity.

The operation is as follows: When the sheet metal has been placed in position on the die, the attendant closes the switches a and b by pressing a push button with each 100 hand. This establishes a circuit through the magnet 11, switch 21, and switches a and b. The magnet 11 being thus energized, pulls its core downward, and, through its connections with the cam lever 7, pulls the latter 105 into position to permit the operation of the clutch, thereby causing the operation of the punch carrier 3. The operator now releases the push button switches and permits a return of the cam lever 7, which, as the pulley 110 P completes a revolution, engages the cam 9 and releases the clutch, the parts being thus

brought again to their initial position. The operator now grasps the handle 20 of the pick-off device, and by closing the push button switch 19, energizes the magnet 17. At 5 the same time the lever is swung inward, so that the magnet cores 18 take hold of the sheet iron punching and scrap. The lever is then returned and the push button switch 19 released. As the contacts of the switch 10 21 are separated when the pick off device is swung inward beneath the punch carrier, the circuit through the magnet 11 can only be established and the punch operated when 15 the pick off device is withdrawn from beneath the punch and carried to a safe position.

It will be apparent that the safety features comprised in the present invention are adapted for use with various forms of 20 punching machines. As shown, for example, in the patent to Scott and Gale, 948,382, February 8, 1910, the pick-off device may be automatically operated, and various other 25 automatic features and other modifications and approved devices are adapted to be used in conjunction with the novel features of the present invention. Various modifications of the safety apparatus herein shown might also be employed without departing 30 from the spirit and scope of my invention. I wish therefore not to be limited to the exact construction herein disclosed.

What I claim as new and desire to secure by Letters Patent of the United States is:— 35 1. The combination of a punch press, a pick-off device, and means for preventing the operation of the punch press when the pick off device is in an interfering position.

2. The combination of a punching machine comprising a vertically reciprocating punch carrier, a pick-off device movable into position to remove the punchings, and means automatically to prevent the operation of the punch carrier while the pick-off device 45 is beneath said carrier.

3. In combination, a punching machine comprising a punch carrier, an electro-magnetic pick-off device adapted to remove punchings from the press, and means to prevent the operation of the punch carrier while the pick-off device is in the path of the punch carrier.

4. The combination of a punching machine comprising a punch carrier, and a die 55 plate, power mechanism to operate the machine, an electromagnet controlling the operation of said power mechanism, a switch in the circuit of said electromagnet, and a pick-off device connected to and controlling 60 said switch to prevent the operation of the punching machine while the pick-off device is between the punch carrier and die plate.

5. In combination with a punching machine, an electromagnet controlling the operation thereof, a plurality of manual 65 switches in circuit with the electromagnet winding, a pick-off device, and a switch in said circuit operated by the pick-off device.

6. The combination with a punching machine, of operating mechanism therefor, a 70 pick-off device, and means to prevent the operation of the punching machine except when the pick-off device and both hands of an attendant are in predetermined safe positions.

7. In combination with a punching machine, an electro-magnetic device controlling the operation of the machine, a plurality of switches in series in the circuit of said magnet, a pick-off device, and an additional 80 switch in series with said first-named switches and operated by said pick-off device.

8. The combination of a punching machine, an electromagnet controlling the operation of said machine, switches in series 85 in the circuit of said machine and employing the hands of an attendant in safe positions when the machine is operated, an electro-magnetic pick-off device, an additional 90 switch in series with said first-named switches, and controlled by the pick off device to prevent the operation of the machine except when the pick-off device is in a safe position, and a switch in circuit with the 95 pick-off electromagnet, the circuit for the pick off electromagnet being in parallel with the first named circuit.

9. The combination of a punching machine, a pick-off device comprising an elec- 100 tromagnet movable into position to take hold of the disks or punchings, a manual switch in circuit with the magnet for energizing the magnet to lift punchings and de-energize the magnet to drop the punchings, 105 and means for preventing the operation of the punching machine during the operation of the pick off device.

10. The combination of a punching machine, an electro-magnetic pick-off device, and 110 a switch in circuit with the pick off magnet to energize and deenergize the magnet for picking off and dropping the punchings, and means for preventing the operation of the punching machine during the operation 115 of the pick off device.

In testimony whereof, I have signed my name to this specification in the presence of two subscribing witnesses.
